UNITED STATES PATENT OFFICE.

THEODORE P. BROWN, OF WORCESTER, MASSACHUSETTS, ASSIGNOR TO SIMPLEX PLAYER ACTION COMPANY, OF WORCESTER, MASSACHUSETTS, A CORPORATION OF MASSACHUSETTS.

VALVE MECHANISM FOR EXPRESSION-CONTROLLING DEVICES OF MUSICAL INSTRUMENTS.

Application filed November 14, 1922. Serial No. 600,858.

To all whom it may concern:

Be it known that I, THEODORE P. BROWN, a citizen of the United States, residing at Worcester, in the county of Worcester and 5 State of Massachusetts, have invented new and useful Improvements in Valve Mechanism for Expression-Controlling Devices of Musical Instruments, of which the following is a specification.

At the present time the leading makers of pneumatically operated, or "self-playing" pianos, aim to produce musical instruments which enable the possessor of one to hear, at any time, substantially the same 10 performance as that of an eminent pianist. An artist's carefully prepared record, produced on a recording piano, is duplicated in the form of a note sheet having side or marginal perforations, which note sheet, 15 when passing over the tracker bar of a piano having valve-controlled mechanism to cooperate with said side perforations, results in repeating the performance of the artist who made the record, with approximate 20 reproduction of his technique, tone, tempo, and pedaling.

To provide an automatic musical instrument capable of faithfully portraying the skill of the artist in the expression of human emotions, is the object of the invention. 25 To this end it is essential that the expression devices of the piano, especially the valves thereof, shall be extremely sensitive to the variations of atmospheric pressure, due to the passage of the side or "expression" 30 perforations of the note sheet over the co-acting openings in the tracker bar. This object is attained by providing for the greatest degree of speed in the operation of the valve, and the elimination of practically 35 all lost motion in said operation.

Further improvements consist in a simplified construction and arrangement of the valves and conduits; also an arrangement 40 whereby the main valves which control the flow of air to cause the proper dynamic effects only open pro rata to the amount of air flowing through them; and also an arrangement whereby the opening movement of the 45 valve is in the direction of the vacuum-induced flow of air.

Of the accompanying drawings forming a part of this specification,—

Figure 1 represents, partly in elevation and partly in section, sufficient parts of the 55 mechanism which include my invention, to enable the same to be understood.

Figure 2 represents a section on line 2—2 of Figure 1, and also illustrates a striking mechanism of the usual type such as employed in a grand piano.

Figure 3 is a view similar to a portion of Figure 1, on a larger scale.

Figure 4 is a view similar to a portion of Figure 2, on a larger scale.

The same reference characters indicate the same parts in all the figures.

A frame 12 (Figure 1) supports the usual music-roll spool 13 from which the note sheet 14 passes, over the tracker-bar 70 15, to the take-up roll 16. The tracker-bar is provided, near each end, with a row of expression ducts 17, and between them is provided with the usual note ducts 18. The note sheet has the usual note openings 19, 75 and is provided with side or marginal expression openings 20, corresponding in number (laterally considered) with the number of ports or ducts 17 in the tracker-bar. Each port or duct 17 communicates by a 80 tube 21 (Figures 2 and 4) with a primary pneumatic 22. In Figure 1, to avoid confusion of lines, each tube 21 is mainly indicated by a dot and dash line. And the usual tubes from the note ducts 18 are omitted. 85 Their usual arrangement is well known.

Each pneumatic 22 controls one of the expression devices employed in the instrument, and it will be sufficient to describe one of them, for instance, the one whose tube 21 90 (indicated at A in Figure 1) is connected with the duct 17, at the extreme left of the tracker-bar. Said pneumatic is connected to and supported by the front cover 23 of the wind chest 24, presently described, two 95 ports 25, 26 leading through said cover. A valve 27, having a short stem 28, is mounted to alternately open or close a port 29, open to the atmosphere, and a port 30 which communicates with the air chamber 31, which 100 latter has the port 26, providing an uncontrolled passageway to the wind chest. One

2
side of the air chamber 31 consists of a diaphragm 32, having a center piece to contact with the valve stem 28. The space at the other side of the diaphragm communicates by a port 33 with the tube 21. In a by-pass port 34 around the diaphragm is located a restricted vent 35.

Within the wind chest 24 is a diaphragm valve 36, one for each expression pneumatic, which cooperates with the nipple end of a conduit 37, the latter communicating with the interior of the choker bellows 38. The movable member of said bellows carries a restricting valve 39, to cooperate with the end of the short tubular conduit 40. A suitably connected spring 41, acts to normally hold the valve 39 unseated.

The main wind chest 42 of the player action communicates with the interior of the bellows 38, by a channel 43, said wind chest being divided in the middle of the instrument by a division wall 44 (Figure 1).

Fastened to the back board 45 of the wind chest (Figures 2 and 4) are the pneumatics 46, which are or may be of the ordinary striker pneumatic type used in player pianos. Associated with said pneumatics I may employ any ordinary system of wires and levers, for actuating the strikers of the piano action, such system being partially indicated in Figure 2, but unnecessary to describe in detail.

In Figures 1 and 3, certain capital letters are applied, one adjacent each tube 21. A description of the operation of the valve mechanism affected by the reduction of air pressure when an expression opening 20 in the note sheet passes over the duct 17, at the extreme left of the tracker-bar, will be sufficient for all. The one selected for this description is the mechanism connected with the tube 21 at the point indicated by the letter A. The tube 21 shown in Figures 2 and 4, is to be understood as the one shown at A in Figures 1 and 3.

As indicated in Figure 1, the expression-control valve mechanisms are arranged in three groups, the one at the left being for the bass accompaniment control, the one at the right for the treble accompaniment control, and the intermediate one for the solo control. As the valve mechanisms of the three groups are substantially the same, the same reference numerals are employed in all, with the exponent ' added for those of the middle group, and the exponent '' added for those of the right hand group.

The three primary valve mechanisms connected with the tubes, indicated at A, F and G, at the left in Figure 1, are connected by tubes, indicated by the dot and dash lines 47, with corresponding primary valve mechanisms of the group at the right in said figure, for a purpose presently explained.

65 The normal condition of the entire mecha-

nism is such that when all the expression ducts 17 are closed by the note sheet, the pressure in the wind chest 24 is slightly lower than the pressure in the interior of the choker bellows 38', and said pressures are such that the instrument will play very soft under the control of any note sheet perforations 19 that may be passing over the note ducts 18 of the tracker-bar. In order to increase the pressure on either the bass or the treble of the instrument, it is necessary to open a passage through one or more of the conduits 37, to permit added pressure to pass through the choker bellows 38, independently of the restricting valve 39. Such added pressure is effected when an expression perforation of the note sheet passes over a duct 17 in the tracker-bar, because atmospheric pressure then acts on the diaphragm 32, overcoming the function of the restricted vent 35, said diaphragm acting on the stem of the valve 27, and moving the latter from its position shown in Figure 4, so as to close the port 29, and open the passageway 30. Owing to the ports 25, 26, the pressure becomes equal on both sides of the diaphragm valve 36, and renders the latter neutral in its relation to the conduit 37, against which it operates, and therefore permits additional air to pass through the conduit 37, and so affect the pressure within the choker bellows 38, independently of the action of the valve 39 (Figure 3), and the spring 41, that the increased pressure affects the vacuum in the main wind chest 42 (the flow of air being as indicated by arrows), and causes all the notes playing in either the bass or treble sections of the instrument to be played with a little greater force whenever an expression opening 20 at the left side of the note sheet is passing over a duct 17, in the tracker-bar communicating with either one of the tubes 21, indicated at A, F and G. The reason why the treble as well as the bass sections will be so affected, is due to the tubes 47 which, as hereinafter explained, connect the primary valve mechanisms of said two sections. It is to be understood, of course, that the primary valve mechanisms in both sections, and also in the solo control section, are, in detail, substantially the same as the one which is fully shown in Figures 2 and 4.

A musical artist frequently accentuates the solo or melody notes independently of the accompaniment notes. In order that such accentuation may be reproduced, it is customary to so arrange the expression devices and note sheet perforations that the pressure in the solo control bellows is always higher than in the bass and treble accompaniment control bellows. The improved structure and arrangement of the devices hereinbefore explained enables the above-mentioned differences of pressure to

be effectively utilized in picking out the solo notes, by means of side perforations 20 in the note sheet, so as to momentarily increase the vacuum pressure on the particular pneumatic 46 that is to play a solo note. Said improved structure includes the diaphragm valves 36, and the conduits 37, and the primary valve system including the diaphragm 32 and the valve 27. The operation 10 of these parts so as to effect instantaneous accentuation will now be described.

For purposes of illustration, assume that in order to play a piece mezzo forte, there are expression openings 20 in the note sheet 15 in position to cause two of the valves 36 to open two of the conduits 37 in the solo control section, and one in the bass control section, and one in the treble accompaniment control section. If now a particular note is 20 to be emphasized without affecting the other notes, the note-sheet opening 19, which is to effect playing of that note, is located either slightly beyond or behind the line of note-sheet openings which effect playing of the 25 rest of the notes in the chord. Assuming that the solo note to be emphasized is in the treble section of the instrument, one of a row of special small perforations 20", in the treble side of the note sheet (Figure 1) 30 opens a duct in the tracker-bar which, by a tube 21", causes a pneumatic to effect opening of the large diaphragm valve 36", in the same manner as hereinbefore described, in connection with the diaphragm valves 36. 35 Said valve 36" cooperates with a relatively large conduit 37", so that when open, a complete and free flow of air is permitted from the interior of the treble wind chest 42, thereby causing any note-striking pneumatic connected with that chest to operate with increased force.

It will be noticed that in each of the three expression-control sections, one of the conduits 37, 37', 37" is larger than the others, 45 and that each diaphragm valve cooperating thereof is also larger than the others. The primary pneumatics which affect the large diaphragm valves 36, 36' of the bass and solo-control sections, are connected by tubes 50 indicated in Figure 1 at E and N, respectively, with ducts in the tracker-bar which are controlled by special side openings in the note sheet. The varying sizes of the conduits and diaphragm valves just described, enable a greater variation in musical effects to be obtained than if all were of the same capacity.

By providing the nipples of the conduits 37, so that they extend into the wind chest 60 24, their ends which form valve seats, are so near the opposite wall of the wind chest which supports the diaphragm valves 36, that the latter need to move no farther from their seats than is absolutely necessary to 65 perform their functions. They only open

pro rata to the flow of air passing through the conduits. Said valves 36 have no working parts associated with them, and they act directly against the ends of the conduits.

As has been explained, the front cover 23 of the wind chest carries all of the diaphragm pneumatics 36 on its inner surface, and is removable from position opposite the conduits 37. All of the primary pneumatics 22 are also carried by the said cover 23, on 75 the outer surface thereof. By removing said cover 23, all of the diaphragm pneumatics 36, and conduits 37, can be readily inspected, and this without disturbing the primary pneumatics 22 from their proper relative positions 80

I claim:

1. A valve mechanism for expression-controlling devices for musical instruments having wind chests provided with conduits extending into them, said conduits being of different sizes and capacities and presenting valve seats at their inner ends, and diaphragm pneumatics of correspondingly different sizes and capacities, positioned upon 90 the opposite wall of said wind chests and constituting valves cooperating with said valve seats.

2. A valve mechanism for expression-controlling devices for musical instruments having wind chests provided with conduits extending into them, said conduits being of different sizes and capacities and presenting valve seats at their inner ends, diaphragm pneumatics of correspondingly different sizes and capacities, positioned upon 100 the opposite wall of said wind chests and constituting valves cooperating with said valve seats; primary valves for controlling said diaphragm valves, and connections for effecting actuation of the primary valves by expression perforations in a note sheet.

3. In a valve mechanism for expression-controlling devices for musical instruments, a wind chest having a plurality of compartments and provided with a removable front cover common to all said compartments, diaphragm pneumatic valves carried by said cover, and conduits of different 110 sizes and capacities extending into the wind chest from the rear thereof, with their ends in position to constitute seats for said diaphragm pneumatic valves.

4. In a valve mechanism for expression-controlling devices for musical instruments, a wind chest having a removable front cover, diaphragm pneumatic valves carried on the inner side of said cover, primary pneumatics for actuating said valves being supported 125 on the outer side of said cover, and conduits of varying sizes extending into the wind chest from the rear thereof, with their ends in position to constitute seats for said diaphragm pneumatic valves.

5. In a valve mechanism for expression-controlling devices for musical instruments, a wind chest having a removable front cover, diaphragm pneumatics carried at the inner side thereof, primary pneumatics supported by the outer side thereof, said cover having ports to provide communication between the primary pneumatics and the spaces both sides of the diaphragm pneumatics, and conduits extending into the wind chest from the rear thereof, with their ends in position to present valve seats for the diaphragm pneumatics.

6. In a valve mechanism for expression-controlling devices for musical instruments, the combination with the wind chest thereof, having a plurality of chambers capable of retaining pressure of different intensities, of valve-controlling means for each expression chamber, the said chambers having a removable front cover common to all of them, said removable cover having a series of expression-controlling primary pneumatics supported by the said removable cover, and means for maintaining the same pressure in the individual primary pneumatic chamber as exists in its corresponding expression chamber.

7. In a valve mechanism for expression-controlling devices for musical instruments, the combination with a wind chest having several compartments therefor, a series of expression-controlling primary pneumatics, each series of expression-controlling primary pneumatics being in communication with its particular compartment of the wind chest, and each primary pneumatic having an air chamber in free communication with the wind chest, a diaphragm forming one side of said chamber, a passageway having a valve and leading to the wind chest, said valve being in a position to be actuated by said diaphragm, and a port communicating with the space at the other side of the diaphragm for said valve.

8. In a valve mechanism for expression-controlling devices for musical instruments, a wind chest having a plurality of compartments, a cover board common to all of said compartments, conduits of variable sizes and capacities in each of said compartments, said conduits extending through the front side of the back board of the wind chest and presenting valve seats, diaphragm pneumatic valves carried on the back side of said cover board and coacting with said valve seats, said diaphragm pneumatic valves being of different sizes and capacities to correspond with said conduits, and primary valve mechanisms secured to the front side of said cover board, and arranged to be controlled by expression perforations of a note sheet.

9. In a valve mechanism for expression-controlling devices for musical instruments,

a wind chest provided with a plurality of compartments, each compartment having in communication therewith a regulating bellows located at the rear thereof, conduits connecting the interior of the respective regulating bellows with the interior of the respective compartments, said conduits extending into the compartments to present valve seats, diaphragm valves positioned on the back side of a removable front cover board to coact with said seats, said front cover board being common to all the compartments, and primary valves secured to the front side of the said cover board and arranged to be controlled by expression perforations of a note sheet.

10. In a valve mechanism for expression-controlling devices for musical instruments, a wind chest having several different chambers capable of retaining different given pressures, said wind chest having a removable front cover common to all the chambers, conduits extended into the said chambers, and diaphragm pneumatic valves located on said removable front cover and positioned to engage the ends of said conduits.

11. In a valve mechanism for expression-controlling devices for musical instruments, a wind chest comprising several compartments, each compartment having conduits of different sizes and variable capacities extending into them, each of said conduits being arranged to present a valve seat at its inner end, a diaphragm pneumatic valve positioned on the opposite wall of the wind chest and constituting a valve cooperating with said valve seat, and a primary valve for controlling each of the said diaphragm pneumatic valves, the arrangement of the said valves and conduits being such that the said diaphragm pneumatic valves in operation will only leave their valve seats proportionate to the induced flow of air created by their release.

12. In an automatic musical instrument, an expression device characterized by having a common wind chest divided into several compartments, each compartment being capable of retaining a given pressure by means of a regulating pneumatic for each compartment, said regulating pneumatics being positioned on the back side of the said wind chest, the said wind chest having conduits in each of the compartments connecting the interior of the said wind chest with the interior of the regulating pneumatics, a front cover for the said wind chest, said cover being common to all the compartments and having on its inward face diaphragm pneumatic valves positioned to engage the ends of said conduits, and primary pneumatic means on the outside of said cover for controlling the action of said diaphragm pneumatic valves.

13. In a regulating device for controlling

the expression of automatic musical instruments, a main wind chest divided into several compartments, each compartment being capable of retaining a pressure of a given intensity, means located on the back side of said wind chest for regulating a given flow of air through the said wind chest, conduits of various capacities located in the wind chest and communicating with the interior of said means for regulating the flow of air, and diaphragm pneumatic valve means positioned on a removable front cover common to all the compartments of the said wind chest, said pneumatic diaphragm valve means being controlled by primary valve

means located on the outside of the said cover and connected to the interior of the said compartment of the wind chest and to the interior of the said diaphragm pneumatic valve means, the said primary valves controlling the operation of the said diaphragm pneumatic valve as governed by the note sheet whereby the intensity of the pressure in a given compartment of the expression device is changed as controlled by the said note sheet. 20 25

In testimony whereof I have affixed my signature.

THEODORE P. BROWN.
